UNITED STATES PATENT OFFICE.

FRANK E. COATSWORTH, OF LINCOLN, NEBRASKA.

JACKET FOR INCUBATOR LAMPS.

Application filed July 17, 1928. Serial No. 293,468.

My invention relates to lamp jackets for incubator lamps and its primary object is the provision of a lamp support which is so arranged as to reduce to a minimum all danger connected with the use of such lamps.

An important object of my invention is the provision of a hinged base for supporting the lamp, the base being provided with a latch which must be released in order to 10 move the lamp to a safe place for filling the lamp.

Another important object which I have in view is the provision of a novel form of latch for the base, the latch being so designed that accidental unlatching is impossible.

Another object of the invention is the provision of a lamp jacket of such design that the lamp cannot be filled while it is in place 20 on the incubator, the filler plug being inaccessible while the lamp is in operative position.

Having in view these objects and others which will be pointed out in the following 25 description, I will now refer to the drawings, in which

Figure 1 is an illustration of the lamp jacket and showing the lamp in its operative position within the jacket.

30 Figure 2 is a view in side elevation of the lamp jacket and of the lamp as they appear while in use.

Figure 3 is a view similar to Figure 2 but showing the position of the base in its relation to the jacket when it is desired to release 35 the bail latch.

Figure 4 is another view similar to Figure 2 but showing the bail released from engagement with the base so that the base may 40 be dropped on its hinge.

Figure 5 is another view similar to Figure 2, but showing the base entirely released so that the lamp may be inserted or withdrawn.

Figure 6 is a view in perspective of the 45 base of the jacket and showing particularly the rib construction on its inner side.

The heater shown in the drawings is the conventional water heater for hot water incubators but it will be evident from the 50 following description that the structure described is equally applicable to air heaters or other types of heaters. As shown, the heater includes a water receptacle 10 having a central flue 11 for the upward passage of 55 the gases of combustion. The water receptacle is provided with a pair of wings 12

having means whereby the water heater and the lamp support may be secured to the outer wall of the incubator.

Secured to the back of the water receptacle 60 is the jacket 13, this extending downwardly to some distance therefrom. The back wall 13 of the lamp jacket is substantially semi-cylindrical in form and of a size such that the lamp 14 may fit freely therein with the 65 lamp chimney 15 projecting upwardly a short distance into the flue 11. The supporting base 16 of the lamp jacket is hinged to the rear wall 13 at 17 so that it may occupy either the position shown in Figure 2 or that 70 shown in Figure 5. The structure of the base is best shown in Figure 6, the base being pan-shaped and having one or more supporting ribs 18 which terminate slightly below the top edge of the base so that the lower 75 edge of the lamp 14 will be seated slightly within the base 16 as shown in dotted lines in Figures 2, 3 and 4.

The latching device for latching and releasing the base 16 comprises a bail 19 of 80 the form which is best shown in Figure 1, the illustration being slightly exaggerated in order to emphasize the construction of the bail and its relation to the lamp jacket and base. As will be seen from that figure, the 85 bail 19 has its lower horizontal portion of a length less than the diameter of the base 16 so that the rearward movement of the bail is limited. The bail is hinged at 20 to the lamp jacket preferably through rivet 90 eyelets for strengthening purposes. The length of the side arms of the bail is such that the forward movement of the bail necessitates the lifting of the forward end of the base 16 in the manner shown in Figure 3. 95 In other words, these side arms determine the radius of movement and this radius is less than the distance from the pivot to the forward lower edge of the base 16. For additional protection I employ a pivoted 100 latch 21 but the bail arrangement as described is alone sufficient to prevent any accidental displacement of the lamp.

The lamp is seated on the base 16 and within the jacket 13 in such a manner that 105 the filler plug 22 is inaccessible while the lamp is within the jacket. In order to fill the lamp it is necessary to entirely remove the lamp from the jacket, and the hinged base makes it absolutely impossible to utilize 110 the base as a temporary but insecure support while pouring oil into the lamp. To

remove the lamp, it is necessary to force the forward end of the base upwardly in order to provide sufficient clearance for the bail 19. When this is done, as shown in 5 Figure 3, the bail may be made to clear the base as shown in Figure 4 and the lamp must then be supported by hand when the base drops as shown in Figure 5. The user then has no alternative but to remove the lamp 10 entirely to some more suitable support while filling it. He then returns the lamp to the position shown in Figure 5, thrusts the chimney upward to the flue 11 and then raises the base to a sufficient height so that he can 15 force the bail into its latching position. There is no danger of his forcing the bail rearwardly to such an extent as to permit the base 16 to drop because the bail is so proportioned that its rearward movement is 20 limited. This construction also prevents accidents which might occur by careless displacement of the bail while the lamp is in use. Nor can the bail be moved forwardly without conscious effort on the part of the 25 operator, its relation with the base being such that the forward portion of the base must be lifted before the bail latch can be released. The lamp chimney 15 extends into the flue 11 a sufficient distance so that the 30 lamp cannot be withdrawn from the jacket without first dropping the base 16. This also is important as careless operators would otherwise be tempted to rest the lamp on the free edge of the base while filling it.

35 Having thus described my invention in such full, clear, and exact terms that its construction and operation will be readily understood by others skilled in the art to which it pertains, what I claim as new and 40 desire to secure by Letters Patent of the United States is:

1. A support for incubator lamps including a jacket, a member projecting forwardly from the upper portion of said jacket and 45 secured thereto, said member being adapted to encircle the top portion of the lamp chimney, a forwardly projecting base hingedly secured to said jacket and adapted to support the lamp, and a releasable latch for holding said base in supporting position.
2. A support for incubator lamps including a jacket and a forwardly projecting member secured to the upper portion thereof, said member being adapted to encircle the 55 top portion of the lamp chimney, a forwardly projecting base hingedly secured to said jacket for supporting the lamp, the distance between said member and said base being such that the lamp can not be removed

while said base is in supporting position, and 60 a releasable latch for holding said base in supporting position.

3. A support for incubator lamps including a jacket and a forwardly projecting member secured to the upper portion thereof, 65 said member being adapted to encircle the top portion of the lamp chimney, a forwardly projecting base hingedly secured to said jacket for supporting the lamp, and a bail having its end portions pivotally secured 70 to said jacket and depending therefrom, said bail being adapted to engage the under side of said base for holding said base in supporting position.

4. A support for incubator lamps including a jacket and a forwardly projecting base hingedly secured thereto, said base being adapted to support an incubator lamp when said base is in horizontal position, a depending bail pivotally connected at its free 80 extremities to said jacket and having a horizontal holding portion for engaging the under side of said base when said base is in supporting position, the length of said holding portion being less than the diameter of 85 said base whereby the rearward movement of said bail is limited.

5. A support for incubator lamps including a jacket and a forwardly projecting base hingedly secured thereto, said base being 90 adapted to support an incubator lamp when said base is in horizontal position, a depending bail pivotally connected at its free extremities to said rear wall and having a horizontal holding portion for engaging the 95 under side of said base when said base is in supporting position, the length of said holding portion being less than the diameter of said base whereby the rearward movement of said bail is limited, the radius of movement of said bail being less than the distance from the pivots thereof to the forward edge of said base.

6. A support for incubator lamps including a jacket of semicylindrical form and a forwardly projecting member secured to the upper portion thereof, said member being adapted to encircle the top portion of the lamp chimney, a forwardly projecting pan-shaped base hingedly secured to said rear 105 wall for supporting the lamp therein, and a bail having its end portions pivotally secured to said jacket and depending therefrom, said bail being adapted to engage the under side of said base for holding said base in supporting position.

In testimony whereof I affix my signature.
FRANK E. COATSWORTH.
